SHOE PRESS PAD

Leonard E. Best, East Orange, N. J., and Willard C. Durham, Winchester, Mass., assignors, by direct and mesne assignments, to Compo Shoe Machinery Corporation, Boston, Mass., a corporation of Delaware

Application July 26, 1935, Serial No. 33,320

16 Claims. (Cl. 12—38)

This invention relates to inflatable pads adapted for use in shoe presses of the kind used for sole pressing operations such as cement outsole affixing, sole leveling, channel laying, and the like.

5 A primary object of the invention is to provide a shoe press pad capable of giving improved performance in the cement affixation of soles to lasted uppers.

10 More particularly, objects of the invention are to provide a shoe press pad which is adapted firmly and fully to fit and press against the sole of a shoe and to impart accurately distributed sole affixing pressure thereto with a materially 15 minimized consumption of air.

Another object of the invention is to provide a press capable of giving improved performance, which at the same time is capable of ready and economical manufacture in quantity.

20 A further object of the invention is to provide a method of making a press having the above and other herein described advantages.

Other objects of the invention will in part be obvious and will in part appear hereinafter.

25 The invention accordingly comprises the several steps and the relation of one or more of such steps with respect to each of the others, and the article possessing the features, properties, and the relation of elements, which are exemplified in 30 the following detailed disclosure, and the scope of the application of which will be indicated in the claims.

For a fuller understanding of the nature and objects of the invention reference should be had 35 to the following detailed description taken in connection with the accompanying drawings, in which:

Fig. 1 is a side elevation of a shoe press equipped with an inflatable pad embodying principles of the present invention, the lower part 40 thereof being shown in section better to illustrate the pad construction;

Fig. 2 is a perspective view of the inflatable pad per se;

45 Fig. 3 is a longitudinal vertical sectional view taken along line 3—3 of Fig. 2;

Fig. 4 is a transverse vertical sectional view taken along line 4—4 of Fig. 3;

Fig. 5 is a transverse vertical sectional view 50 taken along line 5—5 of Fig. 3;

Fig. 6 is a vertical transverse sectional view taken along line 6—6 of Fig. 3; and

Fig. 7 is a vertical transverse sectional view taken along line 7—7 of Fig. 3.

55 In the manufacture of cemented shoes, it is

customary to place an outsole against a lasted upper with cement therebetween and to press these parts together in a shoe press having an inflatable or fluid filled pad in which the fluid pressure is increased in order to urge the upper 5 pad diaphragm against the sole of the shoe. Pressure may also be increased, using such pads, by mechanically or hydraulically forcing the shoe thereagainst. These presses also are useful in other sole pressing operations, such as sole 10 leveling and channel laying.

Heretofore, a common form of pressure pad has comprised a soft rubber bladder which is generally enclosed in a leather casing and is "inflatable" in that it is adapted to have its interior 15 pressure increased in a suitable manner, such as by any of the above indicated methods. In most sole affixing operations it has been customary, with such previous pads, to utilize an air pressure or its equivalent, of about 55 lbs. per square 20 inch or more. With these previously used leather cased pads, the quality of the work obtained has been found to improve as the pad becomes aged or broken in, continued use thereof forming a 25 pliable or seasoned pocket in the area underlying the shoe which gradually becomes approximately contoured to the general configuration of the bottoms of shoes. This pocketed formation, in an old broken in pad, enables the pad diaphragm more closely to hug the shoe bottom, 30 even at the relatively curved parts such as the shank, and assures improved affixing results.

In accordance with the present invention, there is provided a pad which, even when new, gives sole affixing performance which is equivalent or 35 superior to that obtained with an old broken in leather casing, and this at an average pressure of around 35 lbs. per square inch as compared with the previous pressures indicated.

The present inventors have found that where 40 the pressure is accurately applied, the amount of pressure may be reduced. That is, if full accurate surface contact between the pad and shoe is provided, then lower pressures are effective to produce the required affixing results. By 45 permanently pocketing the pad to approximately the contours of shoe bottoms, so that when even in an inert condition the pad tends to fit against the sole, less pressure is needed than when a non-fitting pad is forced into conformity with 50 the shoe, and this decreased pressure, in the case of the pad about to be particularly described, is equally effective with and even more effective than the higher pressures used with previous forms of pads. Further, the advantages of ac- 55

curate surface contact between the pad and shoe are obtained, within the contemplation of this invention, by providing a sole contacting diaphragm of quite flexible but relatively inextensible rubber, which is adapted readily to accommodate itself to the contours of shoe bottoms, and at least some of such benefits may be obtained with a diaphragm of this kind even when it has no, or else a very slight, preformed pocketed 10 contour.

The pad constructed in accordance with the present invention is molded or otherwise suitably formed from rubber. It comprises an inflatable casing which has no interior bladder but is itself 15 formed with desired areas of flexible elastic rubber, or rubber and fabric. Its flexibility and extensibility are controlled so that these properties preferably obtain in a greater degree in some areas of the pad than in others, all in accordance 20 with the inflating characteristics that are desired. Further, in accordance with the best practice of the present invention, the shoe contacting upper diaphragm of the present molded rubber pad is initially fitted to the general contour of the shoe 25 bottoms with which it is to be used, thus eliminating breaking in, while at the same time providing all the advantages obtaining with a broken in pocketed structure. To this last end, the pad of the present invention is preferably designed 30 for use with right or left shoes only. The illustrated pad shown in the present drawings is intended for use with a left shoe, it being understood that a right shoe pad will have a similar but in a sense reversed symmetrical structure. The 35 upper surface of the pad, particularly at the shank and forepart portions, is conformed to the lines of a broken in leather casing so that the desirable contour obtaining in such casing is utilized at the outset. This can readily be accomplished by making a plaster cast of such a broken 40 in casing and forming a rubber mold therefrom. This cast is preferably further modified in order to idealize the contour of the ultimately molded or cast rubber pad, this modification comprising 45 a suitable revision of the cast contour so as to produce a contour approximating the characteristics of those types of shoe bottoms which are to be operated on. This revision, in the case of a molded rubber pad, comprises decreasing, to some 50 extent, the severity of the curvatures obtaining in the original model, so that the least curved among those shoes that are to be operated on may readily fit within the molded pocket of the finished rubber pad. Also, the pad may be molded 55 from a suitable arbitrarily designed pattern having these desired characteristics as to size and contour. Thus, a given pad may preferably be made for operating on left shoes in women's and misses' styles, although it will be understood that 60 the closeness of the conformity of the pad contour to the shoe may be varied as desired, provided commensurate tolerance is given in the expansibility and conformability of the pad material, so that advantages of the invention can 65 be obtained even when widely different types of shoes are operated on with the same press. In fact, it is contemplated that many of the advantages of the invention are to be obtained by making the pad pocket quite roughly approximate the 70 bottoms of shoes, so that both right and left shoes in an extended variety of styles and sizes may be handled. Further, by providing a pad having an upper diaphragm that is readily flexible, some of the advantages as to accuracy of applied pressure are obtained without pocketing such dia-

phragm at all, or by only slightly accommodating the pad structure to the shoe contour. For example, an advantageous form of rubber pressure pad is provided within the field of this invention by constructing it substantially in accordance with the pocketed form as specifically illustrated while permanently shaping its upper diaphragm to approximate only certain contours of shoe bottoms, as for example their longitudinal contours. However, the greatest advantages are 10 found to accrue when a relatively close fit between the pad and shoe is provided. 5

The pad constructed in accordance with this invention is adapted to be used in any suitable form of complementary press structure. Referring more particularly to the drawings, a pad generally designated 10 is shown in a press 11 having integrally cast therewith a rigid bow member 12 from which depends a toe post 13 and a heel post 14. The heel post has a flat under 20 surface 15 which is adapted to seat over the top of the cone of various lasts, and the entire post is preferably vertically adjustable to a number of different positions by means of any suitable adjusting device such as the cam 14'. The entire press structure as herein illustratively depicted conforms to that shown in the application of William C. Card, Jr., Serial No. 677,899, June 27, 1935, and the heel post adjustment may preferably be of the kind particularly shown in that 30 application. 25

The pad 10, as explained above, is formed of molded or cast rubber and its upper diaphragm comprises a forepart engaging portion 16, a shank engaging portion 17, and a heel engaging portion 18. The forepart and shank portions are molded in general conformity to the bottoms of the shoes to be used thereover, in the present instance, say to the shank and forepart contour of a lady's left shoe. The heel portion 18 is preferably flat, as shown. Further, these various portions have different degrees of extensibility and elasticity, the toe, ball and shank portions being relatively more extensible than the heel portion, as will hereinafter be more particularly explained. 40 45

In the pad illustrated, a combined air inlet and outlet conduit 19 communicates with the interior of the pad through the bottom wall thereof, at a point underlying the forepart of a shoe and somewhat rearwardly of the toe portion thereof. The introduction of air through this conduit tends 50 to expand or dilate the pad, and serves to press its upper diaphragm upwardly against the shoe bottom, as will be readily understood. 55

The rubber, from which the pad is cast, particularly certain top areas, is so vulcanized as to be rather live or elastic, but the walls are made quite thick, being on the order of $\frac{3}{8}$ of an inch in thickness over most of the extent of the upper 60 diaphragm so as to curtail or stiffen its extensibility. This extensibility is further controlled and limited by embodying in the pad diaphragm a layer 20 of fabric. This fabric extends over the entire upper diaphragm and continues around to 65 the under side of the pad, so as to be firmly anchored therein. If desired, the fabric insert also may continue down the vertical sidewalls 35 of the pad in order further to limit their extensibility, although this structure is not specifically 70 illustrated. The fabric is sufficiently loosely woven so as to have some extensibility, while still providing a limiting factor against pronounced distension of the pad. The pad, thus constructed, is able to press up against the shoe sole in full 75

pressing contact, but need not unduly curl around the sides thereof so as to roll the sole edges. Its extensibility is what may be termed pronouncedly limited, as compared, for example, with the 5 highly distensible rubber pads familiarly known in foxing affixing presses for tennis shoes.

The portion of the pad underlying the toe of the shoe, indicated at 21, is preferably made relatively flexible and/or extensible as compared 10 with certain other parts of the pad diaphragm in order to enable the diaphragm to bend up firmly against the toe of the shoe even though lasts having markedly different toe lifts are used. In the present illustrated construction this increased 15 flexibility is obtained by making an air pocket 22 beneath the toe portion of the shoe and thereby separating the pad diaphragm into a relatively thin and hence more flexible top ply 23 and an under ply 24. The under ply 24 is permanently spaced from and of greater extent 20 than the top ply 23, being curved downwardly until it rests against the bottom wall 26 of the pad. An opening 27 affords constant communication 25 between the air pocket 22 and the depression 28 formed by a conduit receiving boss 29 in the bottom wall of the pad to which the conduit 19 is fitted as shown in Fig. 3. The under ply 26 of this toe air pocket merges rearwardly into the pad diaphragm at 30, and from here rearwardly 30 the central depressed or pocketed part of the diaphragm remains closely adjacent the bottom wall of the pad rearwardly approximately to the ball line at 31, and preferably is seated thereon as indicated in Figs. 3 and 6 when the pad is deflated. This air pocket structure at the toe also 35 enables the velocity head or pressure of the in-rushing air initially to press the toe of the shoe against the toe post 13, so that the shoe is held firmly while the pressure against the entire sole gradually increases. It is contemplated that this 40 specific pocketed structure may be disposed with, if desired, but if this is done, suitable provision should be made for assuring requisite flexibility at this portion of the diaphragm. Satisfactory 45 flexibility may be obtained by making such toe underlying portion with substantially the same thickness and other characteristics as the shank underlying portion, or, if preferred, either of such portions may be relatively thinned with respect 50 to the other in order to provide any required flexibility. At the ball line, and rearwardly thereof throughout the shank portion, the shoe pocket of the pad slopes laterally upward as 55 shown at 32 and 33, these respective slopes being contoured to the under portion of the shoe so 60 that in the case of a left shoe pad the slope at 32 is generally somewhat more abrupt than that at 33. These upwardly sloping portions gradually flatten out at the sides of the pad as indicated at 34 (Fig. 6) and merge into sidewalls 35 thereof.

Forwardly of the toe portion, the upper diaphragm rises sharply away from the lower pad wall into the front end portion 36 of the pad 65 which is generally configured so as snugly to fit within the pocket of the press casting as indicated at Fig. 1. An air space 37 thus is provided from the toe part of the shoe forwardly to the front of the pad and the upper diaphragm 70 is slightly convex forwardly of the toe portion as is indicated in Fig. 4.

The shank portion of the upper diaphragm also slopes upwardly away from the bottom pad wall providing an air space at 38, and at the juncture 75 of the rear of the shank portion and the front of

the heel seat portion, indicated at 39, the upper diaphragm levels off into the flattened heel portion 48.

Laterally of the heel portion 48, the upper surface of the pad diaphragm is thinned out as 5 shown at 49 (Figs. 2 and 7), and interiorly of the pad the adjacent wall structures are gradually thickened as shown at 51. This provides a relatively inflexible flat heel seat engaging portion which is subject to elevation more or less as 10 a whole against the bottom of the heel seat of the shoe, through flexure of the thinned out walls underlying sections 40, these walls being thinnest in the areas designated 52 (Fig. 7). Since the heel portion of the upper of a cemented 15 shoe is usually tack-lasted, and likewise is relatively flat and stiff, it is not desirable or necessary to have a flexible diaphragm action at this part of the shoe as is wanted at the more convex and irregularly configured shank and forepart portions. Instead, it is desirable to protect the heel of the shoe against undue pressure, as well as against rolling action of the pad, and to this end it has been customary in the past to insert rigid guard plates at this portion of the shoe press, 20 either within a pocket sewed to the pad casing or else overlying the same at or closely adjacent the heel seat portion.

In accordance with the structure of the present pad, the proper and desired action at the heel is 30 obtained by providing a heel section 48 which is flat and rather stiff and is adapted to be forced vertically upward as a whole during the application of pressure to the pad. Also, a rigid metallic plate 53 may desirably be molded or embedded 35 within the heel section 48 in order further to stiffen it, although this is not essential if such section is made of sufficiently thick and stiff rubber. The extreme rearmost portion of the pad at 43 is formed of solid rubber, thus further limiting the 40 vertical movement of the heel portion 48.

The entire pad may conveniently be molded in 45 separate top and bottom sections joinable along a line 44, as shown in Fig. 1, although the invention is not intended to be limited to this particular form of assembly.

In a typical sole affixing operation, a lasted upper and an outsole are registered with cement therebetween and placed in a press such as that shown in Fig. 1, the pad being deflated during 50 this loading operation. Air is then introduced through the conduit 19, passing therefrom through the orifice 27 and under the toe underlying top ply 23, lifting the latter closely up against the toe portion of the shoe. The entire 55 diaphragm also is urged snugly up against the bottom of the shoe, and the diaphragm construction is such that the pressure first acts to cause it to hug closely up against the convex portions, particularly at the shank, and then to apply pressure over the whole sole after accurate contact therewith has been established. By virtue of its 60 molded structure the pad diaphragm already closely approximates that of the shoe bottom so that no undue amount of extension and repositioning thereof is required. The toe, ball and shank portions of the diaphragm are sufficiently 65 flexible and extensible to assure their ready con-formability to the shoe placed thereover, and the heel portion is vertically movable with these 70 other portions so as to press upwardly against the shoe heel. Because of the pad conformation and structure, the shoe does not tend to slide or tilt either longitudinally or laterally.

Through use of a pad constructed in accord- 75

ance with these principles, it has, as pointed out above, been found possible to obtain sole affixing results equal or superior to those obtained with previously used presses while using the relatively 5 lower air pressures indicated. Further, the entire air cavity within the press is, through the present design, kept to a minimum volume commensurate with the desired diaphragm action, so that the present pad's characteristic economy as to air consumption is enhanced. This not only provides marked economies as to air consumption, but leads to easier and more convenient and rapid operation of the press.

While inflation and deflation of the pad cavity 15 through conduit 19 by means of compressed air is a desirable and suitable way of controlling the pressure of the pad diaphragm, it is contemplated that any suitable form of fluid pressure may be exerted beneath the upper diaphragm, and that 20 the latter may be mounted on the press in any suitable manner for receiving such pressure from beneath, or that the shoe may be pressed against the pad as above indicated.

It will be seen that there has been provided a 25 shoe press pad construction which possesses marked advantages, and which is well suited to fulfil its intended purposes.

Since certain changes in carrying out the above 30 method, and certain modifications in the article which embody the invention may be made without departing from its scope, it is intended that all matter contained in the above description or shown in the accompanying drawings shall be interpreted as illustrative and not in a limiting 35 sense.

It is also to be understood that the following 40 claims are intended to cover all of the generic and specific features of the invention herein described, and all statements of the scope of the invention which, as a matter of language, might be said to fall therebetween.

Having described our invention, what we claim as new and desire to secure by Letters Patent is:

1. A shoe pressing device comprising a diaphragm made of rubber permanently pocketed to 45 approximate the contours of shoe bottoms said diaphragm being so constructed as to size and relative pliability and so supported as to have readily flexible shank and forepart engaging portions and a comparatively stiff heel engaging portion, means for confining fluid beneath said diaphragm, and means for increasing the pressure 50 of the fluid against the diaphragm.

2. A shoe pressing device comprising a diaphragm made of elastic rubber having 55 pronouncedly limited extensibility, which is permanently pocketed to approximate the contours of shoe bottoms, said diaphragm being freely and naturally flexible at its shank and forepart engaging portions, and also being of greater fullness at said portions than at the heel engaging portion, means supporting the edges of said diaphragm, means for confining fluid beneath said diaphragm, and means for increasing the pressure 60 of the fluid against the diaphragm.

3. A shoe pressing device comprising a diaphragm made of elastic rubber of sufficient thickness pronouncedly to limit its extensibility, which is permanently pocketed to approximate the contours of shoe bottoms, said diaphragm having 65 freely flexible shank and forepart engaging portions and a relatively stiffer heel engaging portion, means supporting the edges of said diaphragm, said diaphragm having more fullness 70 between its supported edges adjacent said rela-

tively flexible shank and forepart engaging portions than at the heel to provide greater extensibility at said relatively flexible portions, means for confining fluid beneath said diaphragm, and means for increasing the pressure of the fluid 5 against the diaphragm.

4. A shoe pressing device comprising a diaphragm made of elastic rubber having a fabric insert of limited extensibility embedded therein, said diaphragm being permanently pocketed to 10 approximate the contours of shoe bottoms said diaphragm being so constructed as to size and relative pliability as to have freely and naturally flexible curved shank and forepart portions and a comparatively flatter heel portion, said diaphragm being so supported at its edges as to have 15 greater freedom to wrap up against the shoe bottom at highly curved portions thereof than at the flatter heel portion, means for confining fluid beneath said diaphragm, and means for increasing 20 the pressure of the fluid against the diaphragm.

5. A shoe pressing device comprising a diaphragm made of elastic rubber having sufficient 25 thickness to have pronouncedly limited extensibility and having freely flexible shank and forepart portions which are fuller and more flexible than the heel engaging portion, means supporting the edges of said diaphragm so as to provide greater freedom to wrap up against the shoe bottom at the fuller shank and forepart portions 30 than at the heel, means for confining fluid beneath said diaphragm, and means for increasing the pressure of the fluid against the diaphragm.

6. A shoe pressing device comprising a diaphragm made of elastic rubber which is freely 35 and naturally flexible at its shank and forepart engaging portions and has less thickness and greater fullness at said portions than at the heel engaging portion, means for confining fluid beneath said diaphragm, and means for increasing 40 the pressure of the fluid against the diaphragm.

7. A shoe pressing device comprising a diaphragm made of rubber permanently shaped to 45 approximate the contours of shoe bottoms and having portions of differing effective pliability located so as to provide greatest flexibility at its 50 toe engaging portion, least flexibility at its heel contacting portion, and an intermediate flexibility between said portions, means for confining fluid beneath said diaphragm, and means for increasing 55 the pressure of the fluid against the diaphragm.

8. A shoe pressing device comprising a rubber diaphragm having a relatively thick inextensible heel engaging portion supported laterally by 55 thinner portions, means for confining fluid beneath said diaphragm, and means for increasing the pressure of the fluid against the diaphragm.

9. A shoe press pad formed of rubber and having a pocketed upper diaphragm permanently 60 shaped to approximate the contours of shoe bottoms, said diaphragm having its relatively curved forepart and shank engaging portions freely and naturally flexible and of greater fullness than the heel to provide greater vertical expansibility at 65 said relatively curved portions, the heel portion being comparatively flat and of greater stiffness than said shank and forepart portions, said pad having an interior cavity underlying said shank and forepart portions throughout their entire 70 extent and adapted to contain a pressure fluid, and means controlling the pressure of such fluid.

10. A shoe press pad formed of elastic rubber and having an upper diaphragm permanently 75 pocketed to approximate the contours of shoe 75

- bottoms, and having an interior cavity adapted to contain a pressure fluid underlying the curved shank and forepart portions of said diaphragm throughout their entire extent, the walls of said pad being sufficiently thick to have pronouncedly limited extensibility, and so constructed as to size and location as to provide greater vertical expansibility at the shank and forepart engaging portions of said diaphragm than at the heel engaging portion. 5
- 10 11. A hollow, fluid containing shoe press pad formed of rubber having an upper diaphragm permanently pocketed to approximate the forepart and shank contours of shoes, and having a relatively flat heel underlying portion extending rearwardly from said pocketed portion, the walls of said pad being so constructed as to provide greater expansibility at the pocketed portion of the pad than at the heel. 15
- 15 20 12. A hollow, fluid containing shoe press pad formed of rubber having an upper diaphragm permanently pocketed to approximate the forepart and shank contours of shoes, and having a relatively flat heel underlying portion extending rearwardly from said pocketed portion, the walls of said pad being so constructed as to thickness and location as to provide greater expansibility at the pocketed portion of the pad than at the heel, the thickness of said walls being sufficient pronouncedly to limit their extensibility, and a fabric insert of limited extensibility embedded in said diaphragm. 25
- 30 30 13. A hollow, fluid containing shoe press pad

formed of rubber and having an upper diaphragm permanently pocketed to approximate the contours of shoe bottoms, the toe underlying portion of said diaphragm being thinner than other shoe engaging portions thereof. 5

14. A hollow, fluid containing shoe press pad formed of rubber and having an upper diaphragm permanently pocketed to approximate the contours of shoe bottoms, the toe underlying portion of said diaphragm being thinner than other shoe 10 engaging portions thereof and the heel underlying portion of said pad being less expansible than the forepart and shank engaging portions. 10

15. A hollow inflatable shoe press pad formed of rubber and having an upper diaphragm per- 15 manently pocketed to approximate the contours of shoe bottoms, said diaphragm being of sufficient thickness pronouncedly to limit its extensibility, the toe underlying portion of said dia- phragm being separated to form an interior air 20 pocket having a relatively thin top wall, the lower wall of said air pocket having a port commun- icating with the interior of the pad. 20

16. A hollow inflatable shoe press pad formed of rubber and having an upper diaphragm of 25 sufficient thickness pronouncedly to limit its ex- tensibility, the toe underlying portion of said dia- phragm being separated to form an interior air pocket having a relatively thin top wall, the lower wall of said air pocket having a port com- 30 municating with the interior of the pad. 30
